UNITED STATES PATENT OFFICE.

ORIGENE A. THIBAULT, OF VICTORIAVILLE, QUEBEC, CANADA.

PAPIER-MÂCHÉ TOY ANIMAL AND THE LIKE AND METHOD OF MAKING SAME.

1,270,346.

Specification of Letters Patent. Patented June 25, 1918.

Application filed November 9, 1917. Serial No. 201,135.

To all whom it may concern:

Be it known that I, ORIGENE A. THIBAULT, of Victoriaville, in the Province of Quebec and Dominion of Canada, a subject 10 of the King of Great Britain, have invented certain new and useful Improvements in Papier-Mâché Toy Animals and the like and Methods of Making Same, of which the following is a full, clear, and exact description.

This invention relates to improvements in toy animals, and method of manufacturing same, and especially to articles manufactured of papier mâché, and the object of the 15 invention is to provide for the manufacture of very strong and durable articles at low cost.

A further object is to provide in the manufacture of toy animals a structure in which 20 the legs are inseparably connected to the body, and further a simple and reliable means of connecting the animal to its stand.

In the ordinary course of manufacturing 25 toys, such as papier mâché representations of animals, it has been customary to form the body in right and left halves, and the legs separate. The legs are then connected to the body frequently by the same covering of paper which connects the two halves of 30 the body. It will thus be seen that the structure is comparatively fragile, especially when separated from its base. Difficulty is also experienced in securely attaching the toy to the base.

According to the present invention, the 35 legs are formed substantially integral with each half of the body, and the legs and body are reinforced on each side by a metallic member, which also provides a simple and efficient means for attaching the animal to the base.

In the drawings which illustrate the invention:—

Figure 1 is a longitudinal vertical section 40 of a toy animal.

Fig. 2 is a vertical cross section mid way between front and hind legs.

Referring more particularly to the drawings, 11 designates the body and head of a 45 toy animal, and 12 the legs. A suitable mold is provided in which the body and legs are formed. In the process of manufacture, this mold is filled with a suitable number of layers of moist paper and adhesive. A metal reinforcing member 13 is then covered for a suitable distance toward

each end with layers of moist paper or pulp, and is laid in the mold in arcuate form, so that the reinforcing member is continuous through one front leg, the body, and one 60 hind leg, the ends of the member projecting through the feet. A suitable number of layers of moist paper are now superposed on the first layers and the whole mass subjected to pressure by means of a suitable 65 die. The mold and dies may be heated for the purpose of more rapidly drying and effectively setting the material. The other half of the animal is manufactured in the same manner, and the two halves brought together and secured by a wrapping of moist 70 paper and adhesive. When dry, the animal is suitably decorated.

The final operation is the affixing of the 75 animal to its stand 14, which will obviously vary according to the style of the toy. This is very readily effected by passing the ends 15 of the reinforcing members through suitable apertures in the stand and clenching them over on the under side. For further 80 security, the clenched ends may be held by staples if desired. In the clenching process, the reinforcing members are subject to considerable tension, so that the animal is bound tightly to the stand, and at the same 85 time the papier mâché is brought into compression.

It will be noted that as the animal must be made in halves, each half will include 90 a half of each of the four legs. The reinforcements in one half will be fixed in one front and one hind leg, and these legs will be filled up. In the other half of the mold, the reinforcing member will pass through the remaining front and hind legs, which 95 will also be filled. It will thus be seen that before assembling, the halves each comprise a substantially solid front and rear leg, and a hollow half front and rear leg. When the 100 two halves are assembled, the filled or solid legs of the one unite with the hollow or unfilled legs of the other, so that when finished, the animal consists of a hollow body with four solid legs, which are formed substantially integral with the body from the very 105 beginning of manufacture. The reinforcing members extend approximately in parallel vertical planes from front to rear, and form with the material under compression a structure which may be likened to a truss.

From the foregoing description, it will 110 be readily seen that the finished article is of

great strength and durability. The legs being integral with the body and connected by continuous reinforcing members, there is no danger of their being broken. This 5 enables the animals to be shipped from the factory separate from their stands and assembled after delivery. The saving thus effected in packing and freight is of great importance, as it enables a considerable reduction to be effected in the retail sale price. A further opportunity for saving lies in the fact that stands may be manufactured locally, so as to avoid shipping costs entirely.

10 15 Having thus described my invention, what I claim is:

1. A toy animal comprising a body and leg portions, and a pair of reinforcing members of arcuate form extending longitudinally each through the body and through one front and one hind leg.
2. A toy animal comprising a hollow body and legs, and continuous reinforcing members passing longitudinally through the body and legs and bedded throughout their length in the material of the body and legs.
3. A toy animal comprising a hollow body and legs, and a pair of reinforcing members each continuous through a fore

leg, the hollow body and a hind leg, and bedded throughout their length in the material of the body and legs and projecting through the ends of the legs, and a base secured to the animal by the projecting ends of said reinforcing members.

4. A method of manufacturing toy animals, which consists in forming the animal in two halves, each comprising a half of the body and a half of each of the four legs, inserting a reinforcing member in each half continuous through the front legs, body and hind legs, said reinforcing members occupying alternate legs in the mold parts, filling the legs through which the reinforcing members pass in each half, whereby the unfilled legs of one half will unite with the filled legs of the other half, and connecting the two halves of the animal.

5. A toy four legged animal comprising two juxtaposed sections each including a solid front and rear leg, and a hollow half front and rear leg and half the body.

6. The device of claim 5 with a single reinforcing element in the body and legs of one side of each section.

In witness whereof, I have hereunto set my hand.

ORIGENE A. THIBAULT.
